UNITED STATES PATENT OFFICE

RICHARD W. BEACH, OF INDIANAPOLIS, INDIANA, ASSIGNOR TO BEACH & ARTHUR, INC., OF INDIANAPOLIS, INDIANA, A CORPORATION OF INDIANA

DESIGN FOR PAPER NAPKIN OR THE LIKE

Application filed November 11, 1929. Serial No. 33,406. Term of patent 3½ years.

To all whom it may concern:

Be it known that I, RICHARD W. BEACH, a citizen of the United States, and a resident of Indianapolis, in the county of Marion and State of Indiana, have invented a new, original, and ornamental Design for Paper Napkin or the like, of which the following is a specification, reference being had to be accompanying drawing, forming a part thereof.

The figure is a plan view of a one-fourth portion of a napkin containing the design of my invention, the remaining three-quarters of the napkin being positioned in proper relation to the portion shown as indicated by the dot and dash lines.

I claim:

The ornamental design for paper napkin or the like, as shown and described.

RICHARD W. BEACH.
